UNITED STATES PATENT OFFICE.

HUNTINGTON DOWNER, OF HAYBURN, IDAHO.

SHOE-LACE AND TONGUE-STAY.

No. 878,129.

Specification of Letters Patent.

Patented Feb. 4, 1908.

Application filed February 5, 1907. Serial No. 355,905.

To all whom it may concern:

Be it known that I, HUNTINGTON DOWNER, residing at Hayburn, in the State of Idaho, have invented a new and Improved Shoe-
5 Lace and Tongue-Stay, of which the following is a specification.

My invention provides a simple, inexpensive and easily applied device, adapted to be attached to the tongue or flap member of the
10 shoe, and having such construction whereby the knot of the laces can be firmly and neatly held and at the same time will hold the tongue from slipping to one side or the other and from accidental displacement and where-
15 by the ends of the laces will be neatly sus- tained at the desired position on the foot.

In its more subordinate features, my invention consists in certain details of construction and arrangement of parts, all of
20 which will be hereinafter fully described, specifically pointed out in the claims and illustrated in the accompanying drawings, in which,

Figure 1, is a perspective view of a shoe
25 with my improvement attached and adjust- ed for holding the lace and the tongue. Fig.
2, is a view which illustrates the position
of the cap member while tying the knot in
the lace ends. Fig. 3, is a plan view of the
30 device on an enlarged scale. Fig. 4, is a
longitudinal section thereof, showing the
cap closed and the lace knot held thereby.
Fig. 5, is a similar view showing the cap
raised. Fig. 6, is a transverse section on the
35 line 6—6 on Fig. 3. Fig. 7, is a perspective
view of the several parts of the device.

In the practical application of my invention, the same in its generic construction, may be of different specific shapes, but I
40 prefer to arrange the same as shown in the
drawings, in which the main or body portion
a is in the nature of a rectangular shaped
member, preferably stamped up of spring
steel, and which is secured at one end by
45 rivets or stitching to the shoe tongue T as
clearly shown. This plate is cut with an
opening a', the edge of which is turned up as
at a² to form flange vertical to the body a, in
practice, one-eighth of an inch high, and
50 which forms the retaining flange over which
the ends of the shoe laces are passed during
the act of tying the knot.

The opening a', as will be noticed, has a
substantially semi-circular shape and at the
55 base or transverse wall thereof the plate a is

formed with two oppositely disposed longi-
tudinal upturned ears e—e that form the
journals for the spring clasp or cap member
B, the peculiar construction and its coöper-
ation with the body member a is best shown 60
in Figs. 3 and 4, by reference to which it will
be noticed the member B comprises a body
portion having substantially the shape of
the slot in the member a and having its
curved edges formed with pendent flanges b 65
approximately one-eighth of an inch deep,
and so formed that when the clasp member
B is closed the said flanges will close over the
flange a² as clearly shown in Fig. 4.

The clasp B has upwardly extended ears 70
b² b³ that form the journals for the said
member B which lap the ears e on the plate a
to receive the rivet pintles f—f and the said
ears b² b³ have cam portions b³ b³ that engage
spring tongues a⁴ a⁴ formed in the bottom 75
plate a in such manner that when the clasp
member is turned down in the direction in-
dicated by the arrow on Fig. 5 the said mem-
ber B will be closed and held closed by pres-
sure and when moved back to the vertical or 80
open position it will be spring held to such
position.

From the foregoing, taken in connection
with the accompanying drawing, the com-
plete structure and the manner in which my 85
improvement is used will be readily under-
stood. In tying the laces, the ends are
drawn over the flange on the member a
tightened, and the knot tied at a point over
the base of the slot in the member a and 90
when tied, the said knot is turned into the
said slot with the ends of the laces extended
laterally after which the clasp B is snapped
down over the knot, which holds the knot
securely pressed in the opening, the body of 95
the member being convexed or cup shaped
as at b⁵ to the more securely hold the knot in
place. To untie the knot, access thereto is
readily had by pressing up the member B, to
the position shown in Fig. 5. 100

Having thus described my invention,
what I claim and desire to secure by Letters
Patent, is:—

The combination with a plate having an
opening extending from one end thereof, a 105
flange surrounding a portion of the said
opening, said plate extending at the sides
laterally of the flange and having that end
adjacent the opening therein slotted to form
spring tongues and having ears e adjacent 110

the tongues and in line with the flange thereof, a closure plate having ears b^2 for co-operating with the ears e , said ears b^2 having cam portion b^3 for coacting with the spring tongues a^4 , said plate B having a flange b to fit over the flange on the opposing plate and having a solid portion b^5 to fit over the open-

ing in the said opposing plate, all being arranged substantially as shown and described.

HUNTINGTON DOWNER
